UNITED STATES PATENT OFFICE.

ARCHER L. KNAPP, OF DETROIT, MICHIGAN, ASSIGNOR TO PACKARD MOTOR CAR COMPANY, OF DETROIT, MICHIGAN, A CORPORATION OF MICHIGAN.

DESIGN FOR DOME-LIGHT BEZEL.

Application filed July 7, 1927. Serial No. 22,684. Term of patent 3½ years.

To all whom it may concern:

Be it known that I, ARCHER L. KNAPP, a citizen of the United States, residing at Detroit, county of Wayne, State of Michigan, have invented a certain new, original, and ornamental Design for a Dome-Light Bezel, of which the following is a specification, reference being had to the accompanying drawing, forming part thereof.

The figure is a plan view of a dome light bezel, showing my new design.

I claim:

The ornamental design for a dome light bezel, as shown.

In testimony whereof I affix my signature.

ARCHER L. KNAPP.
